UNITED STATES PATENT OFFICE

EDWARD F. MATHEWS, OF YPSILANTI, MICHIGAN, ASSIGNOR TO L. B. EVANS' SON COMPANY, A CORPORATION OF MASSACHUSETTS

DESIGN FOR A SHOE

Application filed August 7, 1929. Serial No. 32,319. Term of patent 7 years.

To all whom it may concern:

Be it known that I, EDWARD F. MATHEWS, a citizen of the United States, residing at Ypsilanti, in the county of Wayne and State of Michigan, have invented a new, original, and ornamental Design for a Shoe, of which the following is a specification, reference being had to the accompanying drawing, forming part thereof, in which the figure is a side elevation of a shoe showing my new design.

The dominant feature of such design is found in the portion which extends up above the sole outside of the upper which has perforations spaced apart approximately equal distances with a distinctive or contrasting lacing woven through them.

I claim:

The ornamental design for a shoe substantially as shown and described.

EDWARD F. MATHEWS.
